UNITED STATES PATENT OFFICE.

BENJAMIN A. MANSFIELD, OF SALEM, MASSACHUSETTS.

COMBINATION-TOOL.

No. 873,571.

Specification of Letters Patent.

Patented Dec. 10, 1907.

Application filed June 1, 1907. Serial No. 376,746.

To all whom it may concern:

Be it known that I, BENJAMIN A. MANSFIELD, a citizen of the United States, residing at Salem, in the county of Essex and State of Massachusetts, have invented new and useful Improvements in Combination-Tools, of which the following is a specification.

My invention is an improved combination tool providing an efficient cork screw, can 10 opener and bottle opener combined in a single implement which may be compactly folded so as to occupy but little space and enable it to be readily carried in the pocket and the said invention consists in the construction, combination and arrangement of devices hereinafter described and claimed.

In the accompanying drawing, Figure 1 is a side elevation of a combination tool constructed in accordance with my invention, 20 showing the same folded. Fig. 2 is a similar view, showing the cork screw extended from the handle and in position for use. Fig. 3 is a similar view showing the arm which is provided with the can opener and the bottle 25 opener extending from the handle so that either the can opener or bottle opener may be employed. Fig. 4 is a transverse sectional view taken on the plane indicated by the line *a—a* of Fig. 1.

30 In accordance with my invention, I provide a handle 1, an implement arm 2 and an implement 3, the latter here shown as a cork screw. The handle is made of spring steel rod or other suitable material bent in the 35 form of a circle open at one side and having outwardly extending arms 4 at said open side.

The implement arm 2 is flattened on opposite sides, is substantially U-shaped to 40 provide an opening in its central portion and is provided with suitable implements, here shown as a can opener 5 and a bottle cap opener 6. The said arm 2 is provided at its open side with parallel portions 7 which 45 respectively bear against the inner sides of the arms 4 of the handle. The size and shape of the arm 2, with its implements 5 and 6, is such as to enable such arm to be disposed in the opening formed in the center 50 of the handle, and in the same plane with the handle. The tang or stem 8 of the cork screw, or implement 3 extends between the tang or portions 7 of the arm 2. A pivot 9 extends through alining openings in the arms 55 4 of the handle and the tangs of the imple-

ments 2—3 so as to pivotally connect the implement arm and the cork screw to the handle so that either of them may be extended from the handle by the same, while the other is turned within the same, as 60 shown in the drawings. The opening provided in the U-shaped arm 2 is such as to enable the cork screw or implement 3 to be turned into such opening and disposed in the common plane of the handle and arm 2 when 65 the tool is folded, and is not for use as shown in Figs. 1 and 4.

I do not desire to limit myself to the precise construction and arrangement of devices herein shown and described, as modifications may be made therein within the scope of the appended claims.

Having thus described the invention, what I claim as new and desire to secure by Letters Patent is:—

1. A combination tool comprising a handle forming an open ring and having parallel arms at the sides of the opening in one side of the ring, a U-shaped arm to lie in the open ring, having tangs bearing against the arms 80 of the handle and provided with implement devices, an inner implement of the size and shape to enable it to be disposed within the opening formed by the said U-shaped arm and having a tang extending between the tangs of such U-shaped arm the arms of the handle and the tangs of the U-shaped implement arm and the inner implement being pivotally connected together for the purpose 85 set forth.

2. The herein described combination tool comprising a frame forming an open ring and having arms at the sides of the opening in the open side of such ring, a U-shaped arm having a can opener on one side thereof and a 95 bottle cap remover on the other side thereof and further provided with parallel tangs bearing against the inner sides of the arms of the tang, a cork screw to lie in the opening in the said U-shaped arm and having a tang 100 extending between the tangs of such arm, and a pivot extending through and connecting the arms of the handle and the tangs of the implement arm and the cork screw.

In testimony whereof, I affix my signature 105 in presence of two witnesses.

BENJAMIN A. MANSFIELD.
